**SPREADER FOR WIRES IN A CHANDELIER
TYPE LIGHTING FIXTURE**

Yasha Heifetz, Rte. 81, Clinton, Conn.

Filed Feb. 13, 1964, Ser. No. 78,619

Term of patent 3½ years

(Cl. D48—4)

FIG. 1 is a bottom perspective view of a spreader for wires in a chandelier type lighting fixture showing my new design with three arms thereof.

FIG. 2 is a bottom perspective view of the spreader shown in FIG. 1.

FIG. 3 is a bottom plan view of a modified form of the spreader shown in FIG. 1 wherein four arms are disclosed.

FIG. 4 is a bottom perspective view of the spreader shown in FIG. 3.

FIG. 5 is a bottom plan view of a further modified form of the spreader shown in FIG. 1 wherein five arms are disclosed.

FIG. 6 is a bottom perspective view of the spreader shown in FIG. 5.

FIG. 7 is a bottom plan view of a further modified form of the spreader shown in FIG. 1 wherein six arms are disclosed.

FIG. 8 is a bottom perspective view of the spreader shown in FIG. 7.

The undisclosed tops of the four embodiments disclosed are mirror images of their respective bottom appearances.

The fragmentary showing of wires on the drawings are for illustrative purposes only.

I claim:

The ornamental design for a spreader for wires in a chandelier type lighting fixture, substantially as shown and described.
